UNITED STATES PATENT OFFICE.

CARL HADCOCK, OF GLOVERSVILLE, NEW YORK, ASSIGNOR OF ONE-THIRD TO WINNE COUNTRYMAN AND ONE-THIRD TO GRANT STANTON, BOTH OF GLOVERSVILLE, NEW YORK.

RAILWAY-TIE.

1,148,585.

Specification of Letters Patent.

Patented Aug. 3, 1915.

Application filed April 26, 1915. Serial No. 23,866.

To all whom it may concern:

Be it known that I, CARL HADCOCK, a citizen of the United States, residing at Gloversville, county of Fulton, and State of New York, have invented certain new and useful Improvements in Railway-Ties, of which the following is a specification.

Reference may be had to the accompanying drawings, and the reference characters marked thereon, which form a part of this specification.

Similar characters refer to similar parts in the several figures therein.

The principal object of the invention is to securely support a railway rail with freedom for limited downward yielding movement of the rail.

Figure 1 of the drawings is a view partly in side elevation and partly in vertical section, showing two railway rails supported and secured upon a cross-tie in accordance with my invention. Fig. 2 is a vertical cross-section of the same taken on the broken line 2-2 in Fig. 1.

Referring to the drawings wherein the invention is shown in preferred form, 1 is an ordinary railway rail, and 2 is a channeled cross-tie having upright side flanges provided with notches, 3-3, adapted to receive the base of the rail, which notches are of sufficient depth to permit a limited vertical movement of the rail without permitting the base of the rail to escape from the notches.

A pair of levers, 4-4, are pivotally mounted at 5-5 within the channeled tie on opposite sides of the notches, 3-3, which levers, 4-4, have notched or recessed jaws, 6-6, on their neighboring ends adapted to receive the opposite edges of the base-flange of the rail. Stops, 7-7, which may be cross-bolts extending across the tie-channel, are located in the paths of the respective levers, 4-4, to limit the upward movement of the jaws, 6-6, sufficiently to prevent the base of the rail from rising above the level of the top of the side flanges of the channeled tie, and thus escaping from the notches, 3-3. The levers, 4-4, are thus mounted with freedom for downward movement of the jaws, 6-6,

permitting the jaws to yield to a downward movement of the rail, 1.

A coil-spring, 8, is mounted within the channeled tie in position to engage the base of the rail, 1, which spring is adapted to normally support the base of the rail above the bottom of the respective notches, 3-3, and at the limit of upward movement permitted the jaws, 6-6, by the stops, 7-7.

The spring, 8, is preferably made of sufficient strength to yieldingly support the load passing over the rail, but if the rail be subjected to an excessive load, the bottoms of the notches, 3-3, afford a positive support for the rail, should the spring be unable to support the entire load.

The spring, 8, is preferably inclosed and supported by a barrel, 9, mounted upon the bottom of the channeled tie between the upright side flanges of the tie.

What I claim as new and desire to secure by Letters Patent is—

1. In a device of the class described, and in combination, a channeled cross-tie notched on its upper side to receive the base-flange of a rail; a pair of levers pivotally mounted within the channeled tie on opposite sides of said notch, said levers having recessed jaws adapted to engage the opposite edges of the base-flange of the rail and being mounted with freedom for downward movement of said jaws; stops in the paths of said levers to limit the upward movement of said jaws; and a spring mounted within the channeled tie in position to engage the bottom of the rail and to support the rail normally above the bottom of the notch in the tie.

2. In a device of the class described, and in combination, a channeled cross-tie having upright side flanges notched to receive the base-flange of a rail; a pair of levers pivotally mounted within the channeled tie on opposite sides of said notch, said levers having recessed jaws adapted to engage the opposite edges of the base-flange of the rail and being mounted with freedom for downward movement of said jaws; stops in the paths of said levers to limit the upward movement of said jaws; a spring-supporting

barrel mounted upon the bottom of the
channeled tie in line with said notches; and
a coil-spring mounted within said barrel
adapted to engage the bottom of the rail and
5 to support the rail normally above the bot-
tom of said notches.

In testimony whereof, I have hereunto set
my hand this 6th day of April, 1915.

CARL HADCOCK.
